UNITED STATES PATENT OFFICE

WILLIAM BADEN, OF STOCKTON, CALIFORNIA

VALVE COOLING DEVICE

Application filed September 29, 1931. Serial No. 565,721.

This invention relates to the poppet type valve of internal combustion engines and particularly to a means for keeping the valves relatively cool when in operation.

It is well known that practically all valve troubles such as warped valves and the failure of the same to seat properly are due to excessive heating of the valves, especially the stems. The stems elongate when highly heated and the necessary clearance between the stems and the push rods is destroyed causing the valves to be held open. The stems also expand in diameter, causing them to stick in their guides, and the valve heads expand, relative to their seats, causing improper seating. It is also recognized that such troubles are largely, if not entirely, eliminated by circulating a cooling medium through the valve stems and heads while the engine is in operation, and various attempts have been made to accomplish this.

As far as I am aware however all such previous attempts necessitated the employment of a special form of valve or push rod or an arrangement for mounting these parts or operating the valves different from standard practice, and which rendered such devices impracticable from a commercial standpoint. The principal object of my invention therefore is to provide an oil cooling arrangement for the valve heads and stems which avoids the above objectionable features in that an operating mechanism of standard form and valves and push rods of the standard conventional type may be employed. The valves are free to rotate as is desirable and may be removed as readily as is now the case without disturbing any part of the cooling structure. The device may also be installed in any gas engine whether of the L or T head type or the overhead valve type, by merely doing a certain amount of work to the valves and the push rods or rocker arms without actually having to replace these parts with others of a different form or design. The device therefore may not only be incorporated in any engines without necessitating any changes in engine design, but may be readily installed in any engine already in use.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a sectional elevation of my oil cooling device as applied to a valve of an L head engine.

Fig. 2 is a similar view showing the cooling device as applied to a valve of an overhead valve engine.

Referring now more particularly to the characters of reference on the drawing and particularly at present to Fig. 1, the numeral 1 denotes a push rod slidably mounted in its bearing sleeve 2 as usual and provided on its upper end with an adjustable screw 3. The head of this screw forms the engaging means 70 for the lower end of the stem 4 of the valve 5.

In arranging my oil cooling device in connection with the standard parts the screw 3 is bored from top to bottom so as to provide an oil passage 6. A spray nozzle in the form of a tube 7 is secured in the upper end of the screw in central alinement with the valve stem and passage 6, and projects upwardly into the stem which is provided with a relatively large bore 8 in which the tube is disposed in clearance relation. The bore extends from the bottom of the stem into the head which is provided with a relatively large diameter chamber 8a with which the bore communicates. The tube terminates a short distance below the upper end of the chamber as shown in Fig. 1.

The passage 6 communicates with the hollow area 9 in the push rod below the screw 3 from which area a port 10 leads to a circumferential groove 11 cut about the outer periphery of the push rod. This groove communicates with the adjacent end of a fitting 12 secured in the sleeve 2 and to which an oil supply pipe 13 is connected. This pipe 100

leads from and is connected to the oil pressure system found on all modern engines.

When the engine is operated therefore it will be seen that a constant circulation of

5 relatively cool oil under pressure will flow from the pipe 13 up through the nozzle 7 and discharge into the chamber 8a. The oil will then flow down about the tube but inside the valve stem to the lower end of the bore 8.

10 At this end the release of the oil from the bore is had without depending on the clearance between the push rod and the stem by means of radial ports 14 cut in the bottom of the stem and communicating with the bore

15 8. The length and positioning of the groove 11 relative to the fitting 12 and the upper end of the sleeve 2 is such that said groove is always in communication with the fitting and never projects above the sleeve with the

20 vertical movement of the push rod. The oil pressure necessary to force the oil up and out of the nozzle 7 is therefore never disturbed. It will therefore be seen that all standard parts now employed in connection

25 with valve operation are retained and may be easily altered in installing the cooling device on an engine already built. The push rod is free to rotate, the screw 3 may be adjusted, and the valve is also free to rotate, since there

30 is no more direct connection between the push rod and the valve than is at present the case. Also, nothing interferes with the direct axial engagement of the stem with the push rod, so that there is no tendency for the valve to be canted sideways.

In engine operation, the valves of course attain a high degree of heat first, or before the other parts of the engine have reached their normal temperature. The circulation 40 of the cool oil through the valves causes their temperature to be held down and to be built up gradually, the excess heat being carried away by the oil leaving the valve stems. As a result the engine parts attain and hold practically the same temperature and engine operation in various respects is improved.

In connection with the valve of an overhead valve engine the installation or adaptation of the oil cooling device thereto is even simpler than in an L head engine. Such an adaptation is shown in Fig. 2. In this case the shaft 15 which supports the valve actuating rocker arm 16 is already hollow and is connected with the force feed oiling system 50 of the engine; and the rocker arm has a circumferential groove 17 about the shaft which is in communication with the oil passage therethrough.

With an engine of this character the oil feed nozzle 7a depends from the outer end of the rocker arm and into the hollow valve stem 4a. A flexible mounting of this nozzle on the rocker arm is necessary, since it must hang straight with any rocking of the arm. To do this a pocket 18 larger than the nozzle tube

is drilled in the arm from the top to a point near the bottom. The top of the nozzle, which is inserted from above, is flared out as shown at 19 so as to swivelly rest on the bottom of the pocket. The hole in the arm 70 below the pocket and through which the nozzle projects is shaped so that the nozzle may have a certain amount of swivel movement. After the nozzle is in place, the pocket is plugged on top so as to be oil tight. 75

A passage 20 is drilled in the rocker arm or some other suitable form of conduit provided between the pocket and the groove 17. This is the only work which has to be done to apply my cooling device to an engine of 80 this type, since the passage 20 of course provides the necessary communication between the nozzle 7a and the forceful flow of oil constantly circulating through the rocker arm shaft. 85

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 95

Having thus described my invention what I claim as new and useful and desire to secure by Letters Patent is:

1. In combination, a valve having a stem, a valve actuating member engaging the outer end of the stem, said stem being bored from its outer end to adjacent the valve head, a spray nozzle tube secured in said member and projecting into the stem bore in clearance relation thereto, and means to supply 100 a liquid to the member to communicate with the adjacent end of the tube. 105

2. In combination, a valve having a stem, a valve actuating member engaging the outer end of the stem, said stem being bored from 110 its outer end to adjacent the valve head, a spray nozzle tube secured in said member and projecting into the stem bore in clearance relation thereto, a liquid conduit, and passage means in the member from the conduit to the adjacent end of the tube. 115

3. In combination a valve having a hollow stem, a movable hollow actuating member positioned for engagement with the outer end of the stem, a conduit mounted in and projecting from the stem engaging end of the member into said stem and means to feed a liquid to said member. 120

4. In combination a valve having a hollow stem, a push rod aligned with the stem, a tubular adjustable head in the rod to engage the outer end of the stem, a conduit secured in said head communicating with the bore of the same and projecting into the valve stem, a passage in the rod below the head and 125 130

establishing communication between the head and the periphery of the rod, a guide sleeve for the rod covering the outer end of the passage, and an oil conduit connected to the sleeve to communicate with said passage.

5. In combination a valve having a hollow upstanding stem, a rocker arm overhanging the upper end of the stem to engage the same, said arm having an oil passage therein, means 10 to feed a liquid to said passage and a conduit swivelly connected to the outer end of the arm and depending therefrom into the valve stem.

15 In testimony whereof I affix my signature.
WILLIAM BADEN.
